DISPENSING ATOMIZER FOR PERFUME OR THE LIKE

Sonia Jokelson Boris, Paris, France, assignor to Societe Technique de Pulverisation (Step), Paris, France, a corporation of France

Filed Feb. 5, 1959, Ser. No. 54,464

Claims priority, application France Oct. 17, 1958

Term of patent 7 years

(Cl. D83—1)

FIG. 2.

FIG. 1.

FIG. 3.

Fig. 1 is a front perspective view of a dispensing atomizer for perfume or the like, showing my new design, the rear being ribbed substantially like the sides shown;

Fig. 2 is a vertical cross-sectional view thereof taken on line 2—2 of Fig. 1; and

Fig. 3 is a transverse cross-sectional view thereof taken on line 3—3 of Fig. 1.

I claim:

The ornamental design for a dispensing atomizer for perfume or the like, as shown and described.
